JOSEF V. PACHER, OF BROOKLYN, NEW YORK, ASSIGNOR TO THE INTERNATIONAL POSTAL SUPPLY COMPANY, OF BROOKLYN, NEW YORK, A CORPORATION OF NEW YORK

LOCK

Application filed December 16, 1930. Serial No. 502,784.

The present invention relates to locks and more particularly to locks of the pin tumbler type. Heretofore it has been the practice to dispose divided pins in a series of parallel sockets in the lock housing and lock barrel, the lines of division of the respective tumblers being brought into coincidence with the circumference of the barrel by a specially shaped key to open the lock. Experienced locksmiths and burglars acquire a highly developed sense of touch and are often able to open tumbler locks by "feeling" the tumblers or pins individually. Having ascertained the lift necessary to elevate each pin, it is a simple matter to determine the proper combination for opening the lock.

When an attempt is made to open a lock without using a key, i. e., by "picking" the lock, it is necessary to bring the shear surfaces of the locking members in exact alignment with the barrel or cylinder of the lock. In locks of the type to which the present invention belongs this operation is called "feeling", due to the fact that it is necessary to feel or find the line set by the periphery of the shaft which is locked. When picking or feeling this kind of lock, it is first necessary that the shaft be tensioned, that is, turned to set up a shearing effect or establish a shearing line. Then, by means of a wire or other object, the exact shear line for each of the tumblers is felt for.

It is an object of the present invention to prevent opening of the lock by touch or "feel" by interposing between portions of the tumblers transverse intermediate pins cooperating with adjacent pins in pairs in such a way that longitudinal movement of one pin of the pair is transmitted in part to the other of the pair of pins. The manner in which the intermediate pins distribute longitudinal movement in both pins of a pair will be understood from the following description of the invention taken in connection with the accompanying drawing, in which:—

Fig. 1 is a longitudinal section of a barrel lock embodying the interposed intermediate pins;

Fig. 2 is a sectional view taken on line 2—2 of Fig. 1;

Fig. 3 is a section of a modification of the invention as applied to a shaft lock; and

Fig. 4 is a sectional view taken on line 4—4 of Fig. 3.

Referring to Figs. 1 and 2, the housing 11 is provided with a plurality of parallel recesses 12 to accommodate pins 13. Each of the pins consists of three sections 13a, 13b and 13c. The housing is also provided with a longitudinal slot 14 in which are disposed intermediate pins 15 in transverse relation to the tumbler pins. It will be seen that the intermediate pins are interposed between sections 13a and 13b and are of sufficient length to cooperate with two adjacent pins. Each of the sections 13a and 13b is chamfered at that end which contacts with intermediate pins better to permit pivotal movement of the intermediate pins about the fulcra points provided by the ends of the tumbler pins.

Mounted for rotative movement within the housing 11 is a cylindrical barrel 16 having a key slot 17 therein. Radial recesses 18 in the barrel are disposed to align with recesses 12 in the housing and terminate short of the axis of the barrel to provide shoulders 19 upon which the pins may rest when the key 21 is withdrawn from the lock. Springs 22 in the ends of recesses 12 tend normally to force the pins towards shoulders 19 and move the lines of separation between sections 13b and 13c out of alignment with respect to the circumference of the barrel, thus preventing rotation of the barrel except when key 21 is inserted. Upon insertion of the key, the pins are so elevated that the lines of separation are brought into coincidence with the circumferential surface of the lock barrel that the latter may be turned.

In the modification illustrated in Figs. 3 and 4 the relation of the divided pins and intermediate pins is similar to that shown in Figs. 1 and 2. The key slot 17', however, is in the lock housing while the barrel is replaced by the shaft 23 of any machine which may be locked. It will be noted that

the intermediate pins are disposed between the sections 13b and 13c and that the line of separation between sections 13a and 13b must be brought into coincidence with the 5 circumferential surface of shaft 23 before the shaft may be turned. In other respects, the operation of the lock shown in Figs. 3 and 4 corresponds with that by which the lock illustrated in Figs. 1 and 2 may be 10 opened.

It is obvious that any combination of pins of varying lengths may be used and that the axes of the intermediate pins need not be in alignment. It is only necessary that the 15 intermediate pins be interposed between sections of the tumbler pins in such a manner that they cooperate with pairs of tumbler pins. It is also to be understood that suitable face plates cover the lock to prevent access thereto except through the key slot and 20 with a key corresponding to the particular combination of pin lengths.

The function of the intermediate pins in both forms of the invention illustrated is the 25 same. Assuming that the lock is being experimented with for the purpose of "feeling" for the combination, as each pin is lifted the intermediate pin cooperating therewith is rocked about the lowest section of the other 30 of the pair of pins contacting the intermediate pin. Since the intermediate pin has substantial thickness, it is apparent that longitudinal movement of one of the pair of pins will effect some longitudinal movement 35 of the other of the pair. Usually the pins 12, 13, 13a, 13b and 13c are relatively small (1/16" in diameter) and the tolerances allowed for the fit of the shaft in the lock 40 exceedingly small (1/10000 of an inch) so that the slightest misalignment of the pins makes it impossible to turn the shaft. This 45 operation of "feeling" is, therefore, a very delicate one and any object tending to set up interference or false pressure on the lift of the pins will destroy this "feel". Such 50 is the function of pins 15 in the present invention in both forms of which it has been ascertained that this distribution of the lift has the effect of destroying the "feel" and 55 prevents determination of the lock combination. Thus, if any one of the floating pins 15 is moved in the slightest degree, it assumes a diagonal position in relation to the two tumblers with which it cooperates, not 60 only imposing a false pressure on the tumbler being felt, but on its twin as well. Likewise, if the twin is moved, the additional resistance brought into play by the tilting pin 15, taken with spring pressure, seriously interferes with, if it does not absolutely 65 destroy, the "feel" necessary to find the shear line.

While preferred embodiments of the invention have been described and illustrated, 70 it is not intended that the invention be

limited only to the forms shown. The invention is obviously susceptible of other modifications within the terms of the appended claims.

What is claimed is:—

1. A pin tumbler lock comprising a housing having parallel recesses therein; a rotatable member having parallel recesses adapted to align with the recesses in said housing; sectional tumbler pins in said recesses; and an intermediate imperforate transverse pin interposed between sections of said tumbler pins and cooperating with two adjacent tumbler pins. 70

2. A pin tumbler lock comprising a housing having parallel recesses therein and a slot disposed transversely of said recesses; a rotatable member having parallel recesses adapted to align with the recesses in said housing; sectional tumbler pins in said recesses; and an intermediate imperforate transverse pin in said slot, said pin being interposed between sections of said tumbler pins and cooperating with two adjacent tumbler pins. 80

3. A pin tumbler lock comprising a housing having parallel recesses therein and a slot disposed transversely of said recesses; a rotatable member having parallel recesses adapted to align with the recesses in said housing; sectional tumbler pins in said recesses; and intermediate imperforate transverse pins in said slot, said intermediate pins being interposed between sections of said tumbler pins and each of said intermediate pins cooperating with a pair of adjacent tumbler pins. 90

4. A pin tumbler lock comprising a housing having parallel recesses therein; a rotatable member having parallel recesses adapted to align with the recesses in said housing; sectional tumbler pins in said recesses; and an intermediate imperforate transverse pin interposed between sections of said tumbler pins and cooperating with two adjacent pins in abutting relation thereto, said sections being chamfered at the ends which abut said transverse pin. 100

5. A pin tumbler lock comprising a housing having parallel recesses therein; sectional tumbler pins in said recesses; and an intermediate imperforate transverse pin interposed between sections of said tumbler pins and cooperating with adjacent parallel tumbler pins. 110

In testimony whereof I have signed my name to this specification.

JOSEF V. PACHER.
